FIG. 3.

UNITED STATES PATENT OFFICE.

GEORGE M. DEPEW, OF CANANDAIGUA, NEW YORK, ASSIGNOR TO GEORGE V. WILLSON, OF PITTSBURG, PENNSYLVANIA.

MACHINE FOR FORMING TWISTED JOINTS WITH WIRE.

SPECIFICATION forming part of Letters Patent No. 717,551, dated January 6, 1903.

Application filed May 28, 1901. Renewed June 12, 1902. Serial No. 111,327. (No model.)

To all whom it may concern:

Be it known that I, GEORGE M. DEPEW, a citizen of the United States of America, residing in the city of Canandaigua, in the county 5 of Ontario, in the State of New York, have invented certain new and useful Improvements in Machines for Forming Twisted Joints with Wire, of which the following is a true and exact description, reference being had 10 to the accompanying drawings, which form a part thereof.

My invention relates to machinery for twisting the ends of wires together, and is especially adapted for twisting the two ends of 15 the wire together in the formation of a wire hoop.

The object of my invention is to provide simple and efficient mechanism for the purposes above mentioned, and the nature of my 20 improvements will be best understood as described in connection with the drawings in which they are illustrated, and in which—

Figure 1 is a plan view of my machine in what I believe to be its best form; Fig. 2, a 25 sectional elevation on the line 2 2 of Fig. 1; Fig. 3, a sectional elevation on the line 3 3 of Fig. 1; Fig. 4, a cross-sectional elevation on the line 4 4 of Fig. 2. Fig. 5 is a view showing the way in which the wire ends are placed 30 when inserted in the machine to be twisted together. Fig. 6 is an exaggerated view illustrating the nature of the twist or curvature which is preferably imparted to the wire before it is put in the joint-forming machine. 35 Fig. 7 represents the completed joint. Fig. 8 represents a wire hoop having its ends joined by twisting, and Fig. 9 is a view illustrating the mode of operation of the twisting mechanism and also some details of construction.

40 A indicates the framing of the machine, having an opening A' formed in it and supporting shaft-bearings, as indicated at A³ A², at each end of said opening, A³ A² indicating bearings projecting upward from the face of 45 the frame A, and A⁴ indicating a projecting ridge serving as a support and bearing for the outer ends of the swinging arms D.

B is the main driving-pulley of the machine secured on the shaft B', upon which is journaled the gear-wheel B², which has a clutch member B³ projecting from its hub and is free

to move into and out of engagement with the clutch member b³, guided on the shaft B'.

b² indicates a stop-pin projecting from the face of the gear-wheel B² and so arranged as 55 to engage on the edge of the frame A when the gear-wheel B² is uncoupled with the shaft and to clear said edge when it is coupled.

B⁴ indicates a bell-crank lever for moving the wheel B² and its clutch member, said lever 60 being actuated through a link B⁵ by a treadle B⁶, which is normally held to its upper position, that in which the gear-wheel is disengaged with the clutch by the action of a spring B⁷.

C C are short shafts supported in the bearings A³ and having secured to them gear-wheels C' C', both engaged with the gear-wheel B², as shown in Fig. 4. The ends of said shafts C have also secured to them the universal joints (indicated at C²) coupling 70 the shaft C to the shaft C³, the outer ends of which last-mentioned shafts have their bearings in projections D³ of the swinging arms D and have attached to them miter-wheels C⁴.

D D are swinging arms pivoted to the frame 75 D' D' and having their outer free ends resting on the ridge A⁴. They have also attached to their inner ends toothed segments D² D², which are in engagement with each other and which cause all movements of the swinging 80 arms D on their pivots to be synchronous and in opposite directions, so that they are always equidistant from the center line. From the outer ends of the swinging arms D project the bearings D³, already mentioned, and also 85 stud-bearings D⁴, having the cylindrical openings D⁵ for the studs slotted at top, as indicated at D⁶.

D⁷ indicates a spring acting to draw the arms D D together into the position shown in 90 Fig. 1.

E E are miter-wheels in engagement with the miter-wheels C⁴ C⁴ and attached to stud-bearings E' E', turning in the slotted cylindrical bars D⁵ of the bearings D⁴ and formed 95 with transverse slots extending past their centers, as indicated at E². The inner faces of the slots are preferably drawn together and somewhat pointed, as indicated at e² in Fig. 9, so as to engage in the spiral convolutions of the wire, as shown in said figure. The stud-bearings and wheels E are held in

position on the bearings D⁴ by collars, as indicated at E³ E³.

F indicates a bracket bolted on the center of the frame A between the swinging arms D 5 D, having an upward extension forming a fixed jaw F² of a gripping device and supporting a pivot F', on which is pivoted the moving jaw F³ of the gripping device, having a lever extension F⁴, which is connected by a 10 link F⁵ with the treadle F⁶, normally held in its upper position by a spring F⁷, tending to keep the gripping-jaws apart, as shown in Fig. 2.

G, Figs. 5 to 9, inclusive, indicates a spiral 15 wire hoop which, as shown in all of said figures except Fig. 6, is formed as though by winding the wire around a central line.

G' G' indicate the ends of the hoop, and G² indicates the joint formed by twisting the 20 joints together.

In operation the ends of the hoop are lapped and brought together, as shown in Fig. 5. The lapped portion is then inserted between the jaws F² and F³ and into the slots in the 25 studs E'. The treadle F⁶ is depressed, causing the gripping-jaws to seize and hold the wires at the center, and the treadle B⁶ is then depressed, coupling the spur-wheel B² with the driving-shaft B' and causing the engaged 30 gear-wheels C' C' to rotate in the same direction, this movement being imparted through the universal joints C² to the shafts C³ C³ and their miter-wheels C⁴ and imparted to the miter-wheels E E and the grooved studs E' E' 35 as rotative movement in opposite directions, as indicated in Fig. 9. The effect of this is that each rotating slotted stud twists and winds the free end of the wire around the body of the hoop, and as the grooves in the 40 studs are practically in engagement with the twist of the wire the studs and the arms D D supporting them move gradually outward from the center line, following the twisting of the wire until the joint is completed, as shown 45 in Fig. 7. The operator then permits the treadle B⁶ to rise, uncoupling the shaft B' from the gear-wheel B², the stop b² of which arrests it and the parts coupled with it, including the slotted studs, as soon as they 50 have reached the positions indicated in Figs. 1 and 2. At the same time the operator releases pressure on the treadle F⁶, permitting the jaws F³ and F² to move apart, so that the completed joint can be removed from the machine and a new wire placed therein.

Many features of my invention are, I believe, in themselves new, and I do not desire to be understood as limiting myself to the construction shown except where such limitation is clearly expressed in the claims.

Having now described my invention, what I claim as new, and desire to secure by Letters Patent, is—

1. In a machine for twisting the ends of 65 wires together, the combination of two bearing-blocks, movable to and from each other, with rotatable slotted studs, supported on and

movable therewith, and means for rotating the studs in opposite directions.

2. In a machine for twisting the ends of 70 wires together, the combination of two bearing-blocks, movable to and from each other, with constantly-acting means tending to hold the blocks together with yielding pressure, rotatable slotted studs supported on and movable therewith, and means for rotating the studs in opposite directions.

3. In a machine for twisting the ends of 80 wires together, the combination of two bearing-blocks, movable to and from each other, with means regulating such movement so that said blocks are always relatively equidistant from a central point, rotatable slotted studs supported on and movable therewith, and means for rotating the studs in opposite 85 directions.

4. In a machine for twisting the ends of wires together, the combination of two bearing-blocks, movable to and from each other, with means regulating such movement so 90 that said blocks are always relatively equidistant from a central point, constantly-acting means tending to hold the blocks together with yielding pressure, rotatable slotted studs supported on and movable therewith, and 95 means for rotating the studs in opposite directions.

5. In a machine for twisting the ends of 100 wires together, the combination of two bearing-blocks, movable to and from each other, with a stationary wire-gripping device situated between said movable blocks, rotatable slotted studs supported on and movable therewith, and means for rotating the studs in opposite directions.

6. In a machine for twisting the ends of 105 wires together, the combination of the two arms, pivoted to the frame at one end and supporting bearing-blocks at their free ends, with slotted studs journaled in the blocks, 110 means for synchronizing the movements of the arms, and means for rotating the slotted studs in opposite directions.

7. In a machine for twisting the ends of 115 wires together, the combination of the two arms, pivoted to the frame at one end and supporting bearing-blocks at their free ends, with slotted studs journaled in the blocks, 120 means for synchronizing the movements of the arms, a stationary wire-gripping device secured centrally between the free ends of the arms, and means for rotating the slotted studs in opposite directions.

8. In a machine for twisting the ends of 125 wires together, the combination of two movable bearing-blocks, slotted studs journaled in said blocks, a constantly-driven shaft, means for rotating said studs in opposite directions, and a clutch for coupling and uncoupling said means with the constantly- 130 driven shaft.

9. In a machine for twisting the ends of wires together, the combination of two movable bearing-blocks, slotted studs journaled

in said blocks, a constantly-driven shaft, means for rotating said studs in opposite directions, a clutch for coupling and uncoupling said means with the constantly-driven shaft, and a stop for arresting the studs in determined positions when the clutch is disengaged.

5 10. In a machine for twisting the ends of

wires together, the two rotatable slotted studs E' E' having the inner edges e^2 of their slots 10 narrower than the body of the slots.

GEORGE M. DEPEW.
